UNITED STATES PATENT OFFICE.

THOMAS MIDGLEY, JR., OF LANCASTER, OHIO, ASSIGNOR, BY MESNE ASSIGNMENTS,
TO DELCO-LIGHT COMPANY, OF DAYTON, OHIO, A CORPORATION OF DELAWARE.

METHOD OF MAKING HYDROMETERS.

1,381,929.

Specification of Letters Patent. Patented June 21, 1921.

Application filed March 31, 1916. Serial No. 88,164.

To all whom it may concern:

Be it known that I, THOMAS MIDGLEY, Jr., a citizen of the United States, residing at Lancaster, in the county of Fairfield and 5 State of Ohio, have invented certain new and useful Improvements in Methods of Making Hydrometers, of which the following is a specification.

This invention relates to the method of 10 making hydrometers, the particular hydrometer to which this method is applicable is the one shown in my Patent No. 1,335,253, dated March 20, 1920. The invention consists itself in a method whereby these hydrometers may be cheaply made and yet be 15 sufficiently accurate for all practical purposes.

In the accompanying sheet of drawing, I 20 have represented diagrammatically an apparatus by which my method may be carried out and also a representation of the hydrometer itself. In these drawings:

Figure 1 represents a series of receptacles, which receptacles are themselves filled or 25 partially filled with a fluid of known specific gravity. For purposes of convenience, I have designated the specific gravity of the various liquids as progressing arithmetically from 1.2 to 1.8,

30 Fig. 2 shows a hydrometer in its completed state, and,

Fig. 3 shows the two sections forming one of the units of these hydrometers.

My method consists essentially in the provision of standardizing hydrometer units or float members for measuring hydrometers, and these units or float members are preferably constructed of sections as is shown in Fig. 3, which sections are designated 1 and 40 2. The completed units are designated 3 in Fig. 2, and it will be noted that a number of hydrometer units of different specific gravities may be united by a flexible cord 4. A further description of the use of the 45 present invention in the manner shown in Fig. 2 will be found in my co-pending application, Serial No. 71,171, filed January 10, 1916. These various sectional units are introduced into a bath of known specific gravity and those which are then in an unbalanced state are separated from the balanced ones and the unbalanced sectional units are then successively introduced into the succeeding baths. That is, the sectional units 55 which, when introduced into a bath of given

specific gravity tend to sink, are separated from the units which tend to float, and these units which tend to sink are then introduced into the succeeding baths until a bath having a specific gravity, such as will cause the 60 units to float, is found. By this arrangement, the various specific gravities of the various sectional units may be determined. As an illustration, let it be assumed that a bulk of these sectional units are introduced 65 into the bath designated as having a specific gravity of 1.3. Those sectional units which are of a greater density will immediately sink and these may be said to be in an unbalanced state. These are then removed and 70 introduced into the succeeding bath designated as having a specific gravity of 1.4. A portion of these units will more than likely be found to have a greater density and these will sink. The unbalanced units are 75 then successively introduced into the baths of gradually increasing specific gravities until the specific gravity of all of the units has been determined. If it is then desired to form a hydrometer unit which will register 80 a specific gravity of 1.5, the sectional units having a specific gravity of 1.5 may then be united to form a sphere as indicated in Fig. 2. These sectional units may be secured together in any suitable manner, preferably however by being vulcanized together 85 in the proper manner. After this is done, the various combinations of sectional units whose mean value will equal 1.5 will then be 90 united. As an example, the units having a specific gravity of 1.4 and those having a specific gravity of 1.6 may be united, since the mean value of their specific gravity is 1.5. Likewise 1.3 and 1.7 may be united and 95 so on.

It will thus appear that I have provided a method whereby hydrometers may be rapidly and cheaply constructed. It is not intended that the completed hydrometer shall be sensitive to a very high degree, but only 100 so as to serve all practical purposes such as the testing of milk to know whether it has been adulterated or whether it has been skimmed. Likewise, the liquids used in motor vehicles as cooling water, as, for instance, 105 a 20% solution of alcohol and water, may be tested to maintain the correct proportion to prevent its freezing in cold weather.

What I claim, is:

1. The method of making hydrometers of 110

the type specified, which consists in determining the specific gravity of a plurality of sectional units, and then selecting and uniting certain of said units having respectively 5 such specific gravities that each of the completed units thus formed thereby shall have, as a whole, a predetermined specific gravity.

2. The method of making hydrometers of the class described which consists in making 10 the hydrometer units in sections, introducing the various sectional units into a bath of known specific gravity, separating the balanced units from the unbalanced, succes-

sively introducing the unbalanced units into baths of varying but known specific gravities to thereby determine the specific gravity of the remaining sectional units, and finally uniting those sections into a single unit whose mean value equals the value wanted. 15

In testimony whereof I affix my signature 20 in presence of two witnesses.

THOMAS MIDGLEY, JR.
